UNITED STATES PATENT OFFICE.

JOSEPH TRIMBLE, OF PORTLAND, OREGON, ASSIGNOR TO THE BURKE MACHINERY CO., OF PORTLAND, OREGON, A CORPORATION OF OREGON.

WINDSHIELD CLEANER.

Application filed April 28, 1927. Serial No. 187,206.

The invention relates to devices for the cleaning of the transparent member of windshields as commonly adapted to motor vehicles and the like, and consists primarily of, cleaning elements adapted to being reversed to provide wiping elements for the removal of moisture, dust and the like that has a tendency to form upon the transparent member and further provides for a reversing of the cleaning element wherein after the reversal has taken place, to provide one or more cutting elements for the removal of, snow, ice, sleet and other solids that form from time to time upon the transparent member of the windshield.

A further object of my invention consists in providing a simple device that is adaptable to having the cleaning elements reversed upon a supporting and operating arm and to provide cleaning elements adapted to the removal of the liquids or solids, the same being adapted to being actuated by manual or automatic means.

A still further object of my invention consists in providing a device of simple construction, of but few parts, one that will not easily get out of order or out of repair and one that may be adapted to any of the devices now on the market for the manual or automatic cleaning of windshields.

With these and incidental objects in view, the invention consists in certain novel features of construction and combination of parts, the essential objects of which are set forth in the appended claims and a preferred form of embodiment of which is hereinafter described with reference to the drawings which accompany and form a part of this specification.

Of said drawings—

Fig. 1 is a fragmentary front elevation of a windshield, to which is attached a preferred form of embodiment of my device.

Fig. 2 is a perspective end view of the assembled device.

Fig. 3 is a side elevation, with one of the wiping elements partially broken away to particularly illustrate the construction of my device.

Fig. 4 is a view taken on the section line 4—4 of Fig. 3 looking in the direction the arrows point.

Fig. 5 is a view taken on the section line 5—5 of Fig. 3 looking in the direction the arrows point.

Like reference characters refer to like parts throughout the several views.

1 is a transparent member of a windshield encased within the supporting frame 2. The operating arm of my device is shown at 3 which may be attached to a windshield operating device 4 that may be of the manually operated type, or of the automatic type. An eye 5 is formed in the outer end of the arm 3 and the journal pin 6 passes through the eye of the arm and is positioned within the side walls of the device.

I preferably form the encasing side walls of my device of two supporting elements 7 and 8 having outwardly extending bottom surfaces 11 and 12. The supporting elements 7 and 8 have parallel surfaces 9 and 10 that are spaced apart. The outwardly extending side walls being cut, or formed in a manner as shown at 13 and 14 to form a cutting edge of the elements, the object of which is to cut the solid material that has a tendency at times to be deposited upon the transparent element 1 of the windshield. The sloping side walls 11 and 12 aid in the carrying off of the solids after the same has been removed from the transparent surface from which the same is cut or removed by the cutting edges. Inwardly extending surfaces 15 and 16 are formed on the upper part of the parallel side walls 9 and 10 to bring the upper surfaces 17 and 18 in parallel alignment and also spaced apart. A cleaning element 19 is disposed between the surfaces 16 and 17, the same being made of rubber, or other suitable material that is adapted to the removal of moisture, or dust, or liquids that become deposited upon the transparent member 1. The elements 7 and 8 and the elements 19 are maintained in intimate working relation with each other by rivets, or other fastenings, 20 being used to maintain the same together. When it is desired to reverse the device and use the rubber cleaning element to contact with the transparent element of the windshield, the

spring 21, that is held in contact with the side wall of the side member 8 by any suitable fastening means as a rivet 22, is pulled outwardly by engaging the end lip 23 of the spring, thus releasing the journal pin 6 from being locked within the bearings within the side walls and permits its removal therefrom and from the eye 5 of the rod 3. The device may then be reversed and the journal pin 110

be reinserted in place and the spring released to again lock the same in place and in position. To facilitate the locating of the eye 5 in registerable alignment with the holes 5 that form the bearings for the journal pin 6 I place a stop pin 24 through the side walls.

While the form of mechanism herein shown and described is admirably adapted 10 to fulfill the objects primarily stated, it is to be understood that it is not intended to confine the invention to the one form of embodiment herein shown and described, as it is susceptible of embodiment in various 5 forms, all coming within the scope of the claims which follow.

What I claim is—

1. In a device of the class described, the combination of side walls spaced apart, said 0 side walls having cutting edges disposed at their lower edges, a strip of rubber disposed between the side walls and projecting there-

beyond along the upper edge, means for actuating the device and means for reversing the device relative to the actuating and supporting element. 25

2. In a device of the class described, the combination of side wall elements having outwardly extending lower surfaces, a cutting edge disposed on the lower edge of 30 each, a journal pin seated within the side walls, an actuating arm having an eye disposed in its outer end hingedly secured to the journal pin, means for locking the journal pin relative to the side walls, a cleaning strip of rubber or like material disposed between the side walls and projecting therefrom and parallel to the cutting edges of the side walls at its outward edge, and means for reversing the device relative 40 to the actuating lever arm to selectively bring the cutting edges or the rubber like material in contact with the surface to be cleaned.

JOSEPH TRIMBLE.
